UNITED STATES PATENT OFFICE.

GOTTFRIED HEINRICH JACOB MAAS, OF ARNSBERG, GERMANY.

SUSPENDED RAIL-JOINT FOR RAILROADS.

SPECIFICATION forming part of Letters Patent No. 744,868, dated November 24, 1903.

Application filed June 10, 1903. Serial No. 160,925. (No model.)

To all whom it may concern:

Be it known that I, GOTTFRIED HEINRICH JACOB MAAS, civil engineer, federal and architectural counselor, a subject of the King of Prussia, German Emperor, residing at 7 Rumbeckerstrasse, in the city of Arnsberg, Province of Westphalia, Kingdom of Prussia, German Empire, have invented certain new and useful Improvements in Suspended Rail-

o Joints for Railroads, of which the following is a specification.

This invention relates to a suspended rail-joint on a single peculiar metal joint-sleeper for railroads, in which the width of the sleeper depends upon the distance of the supporting-plates in such a manner that the bed on the whole width of the sleeper is subjected to pressure for all loads and is compressed and tightened just below the supporting-plates 20 on packing the ballast, whether the joint be symmetric or not.

In the ordinary superstructure with cross-sleepers the rails and the fish-plates will wear off in their contact-surfaces the quicker the larger the distance between two adjacent joint-sleepers is, and the loaded rail end will bend the deeper than the adjacent still unloaded rail end, which means that the rolling-stock will be shaken on passing from the one 25 rail end over the gap to the other rail end, and the more so the more the wear and tear of the rails and the fish-plates has advanced. Even for quite new superstructures, when the loaded rail end will bend very little below the 30 level of the adjacent unloaded rail end, owing to the support afforded by the strong and unworn fish-plates, the shock given to the railroad-cars by the joint is quite distinct, and it will constantly increase in a considerable 35 degree. Attempts have been made with little success to avoid these defects by placing the two joint-sleepers as near as possible to each other and by reducing the distances between the neighboring cross-sleepers. Of course 40 there was a limit, since it was necessary to leave sufficient space between the two adjacent joint-sleepers to pack the ballast. For the ordinary widths of the sleepers of from two hundred to two hundred and sixty milli- 45 meters it was, however, impossible to reduce the distance between the two joint-sleepers further than four hundred millimeters from center to center. This expedient proving in-

sufficient, it has been tried in superstructures with wooden cross-sleepers to compound 55 the two joint-sleepers and to form of them a single broad joint-sleeper and to place thereon the two supporting plates, which remained distinct; but this trial was in vain. It is true that in this arrangement the two support- 60 points of the two adjacent rail ends can be placed near each other and at pleasure, so as to considerably reduce the deflection of the floating rail end, which according to the well-known formula $\frac{P l^3}{3 E I}$ depends mostly upon 65 the length l of the rail end from the support-point. However, this attempt proved to be without success and was not since repeated, because the wooden sleepers under the two 70 supporting-plates were liable to turning out, and it was impossible to get a rigid base. In opposition to these attempts the following alterations and improvements in the suspended rail-joint are employed according to my in- 75 vention.

First. The cross-sleeper immediately beneath the rail-joint is widened and made of metal, since it is impossible to obtain wooden sleepers of the necessary width and quality 80 out of the logs or timbers at disposal, and the metal sleeper affords the advantage that it will retain the perfect straightness of the common even surface required for receiving the two supporting-plates of the suspended 85 rail-joint, whereas wooden sleepers of a larger width are liable to warping and sloping, so that they are rendered unfit for the uniform support of the two suspended rail ends, which is required for the good passage 90 of the railroad-cars over the joint.

Second. The width of the metal cross-sleepers beneath the suspended rail-joint is so proportioned with regard to the distance of the two supporting-plates from center to center 95 as to prevent the sleeper from turning and to secure it under the load. Although the required width is to be found by calculation, as hereinafter stated, yet it is new to so proportion the width of the sleeper, and thereby 100 to essentially improve on the suspended rail-joint.

Third. The metal cross-sleeper beneath the suspended rail-joint is given a central rib in addition to the lateral wings, which central rib being located vertically between the two

supporting-plates causes the ballast just beneath the two supporting-plates to be mostly compressed on being packed.

Fourth. The unsymmetric suspended rail-joint having a shorter giving-off rail end and a longer taking-up rail end, which is especially to be recommended for double tracks and which hitherto was known in the railroad literature only in connection with two adjacent joint-sleepers, can be placed with special advantage on the single metal cross-sleeper, since the two suspended rail ends of unequal length are given a single and solid basis, which it is impossible to obtain by two adjacent joint-sleepers.

These novelties and improvements in the suspended rail-joint are illustrated in the accompanying drawings, in which—

Figure 1 is a sectional view of a sleeper and the rail-supporting plates thereon in accordance with my invention, portions of two rails and a fish-plate being shown in side elevation. Fig. 2 is a plan, partly in section, of Fig. 1. Fig. 3 is a cross-section through the rail, fish-plate, and sleeper. Fig. 4 is a sectional view of the rail-supporting plate. Fig. 5 is a view similar to Fig. 1, but showing the ends of the rails in a different position relatively to the sleeper and rail-supporting plates. Fig. 6 is a plan of Fig. 5, partly in section. Fig. 7 is a sectional view through the rail, fish-plate, and sleeper shown in Fig. 5. Figs. 8, 9, and 10 are diagrams for the purpose of illustrating certain equations referred to hereinafter.

The hook-nail and plate systems now mostly in use in Germany are shown in Figs. 1 to 7, Figs. 1 and 2 representing the symmetric and Figs. 5 and 6 the unsymmetric rail-joint. In both cases the width of the hollow sleeper S is more than three times the distance of the two supporting-plates V and V' from center to center. Preferably these supporting-plates are slightly curved upward, as is shown at Fig. 4, so that the suspended rail ends, even if very abruptly shortened, may have a sufficient suspending length. In the cross-section shown at Fig. 3 angle fish-plates L L' are assumed in correspondence to Figs. 1 and 2, while in the cross-section shown at Fig. 7 flat fish-plates L' L' are assumed in correspondence to Figs. 5 and 6. In the rail-joint according to the three latter figures the rail-heads do not require to be supported by angle fish-plates, and this construction in which the flat fish-plates are independent of the rail-feet and supporting-plates may be employed if the rails are prevented from moving or shifting on the supporting-plates by other means, such as opposing fish-plates on the intermediate sleepers. Of course the broad cross-sleeper with the suspended rail-joint may also be employed in other superstructures with cross-sleepers—for instance, such having chair-rails, the two cast-iron chairs being placed on the single broad sleeper instead of on two joint-sleepers. In case the

suspended rail ends are abruptly shortened, however, it will be necessary to slightly curve upward the supporting-surface for the lower rail-heads in the chairs, so as to support the rails only in the centers of the chairs.

In proof of the advantages of the present construction of the suspended rail-joint the following statement is made. In the suspended rail-joint on a single wooden cross-sleeper mentioned in the introductory part of this the distance of the two supporting-plates from center to center is two hundred and sixty millimeters and the width of the sleeper four hundred and fifty millimeters. Let P equal the load by a wheel of a railroad-car, $p d$ equal the specific stress on the bed thereby caused, $p z$ equal the specific stress and tug on the edges of the sleeper per square unit resulting from the turning moment. Then according to Fig. 8 the tug on the edge of the unloaded part of the sleeper will be

$$p z = \frac{26}{15} p d, \quad 90$$

so this edge will be lifted from the bed by a specific tug of

$$\frac{26 - 15}{15} p d = \frac{11}{15} p d, \quad 95$$

resulting from

$$p d = \frac{P}{450} \quad 100$$

$$\frac{1}{2} p z \frac{450}{2} \cdot \frac{2}{3} \cdot 450 = P \frac{260}{2} \quad 100$$

$$p z = \frac{26}{15} p d; p z - p d = \frac{11}{15} p d. \quad 105$$

Of course such an unstable joint-sleeper cannot be secure beneath a suspended rail-joint, and presumably this is the reason why a similar construction having been tried in South Italian railroads was not taken up elsewhere. 110

The improvement according to my invention is useful, for the reason that by proportioning the width of the hollow sleeper with regard to the distance of the supporting-plates not only the tilting forces are entirely avoided, but also a solid and secure position of the sleeper is obtained by distributing a proper pressure on the bed over the whole width of the sleeper. In order to cause the under side of the sleeper on its entire width 115 to always exert a pressure on the ballast, it is, according to Fig. 9, necessary that one-half of the width of the sleeper be at least equal to triple the distance of a supporting-plate from the center of the sleeper, for 120

$$P = 2 x p \quad 125$$

$$P \cdot a = p \frac{x}{2} \cdot \frac{4}{3} x = \frac{2 p x^2}{3} \quad 130$$

$$2 x p a = \frac{2 p x^2}{3}; x = 3 a, \quad 130$$

which, for instance, results in a width of the sleeper of six hundred millimeters for a dis-

tance of $a = 100$ millimeters. It is preferable, however, to make the width of the sleeper $2a$ a little larger than $6a$, for in this case not only the uniform stress $p d$ caused by the single load, but also and in a greater degree the stress $p z$ resulting from the bending moment $P a$ will decrease, as is proved by the following equations:

$$10 \quad P = 2 b p d$$

$$P \cdot a = \frac{p z}{2} \cdot b \cdot \frac{4}{3} b = 2 \frac{p z}{3} \cdot b^2$$

$$15 \quad p z = \frac{3a}{b} p d, \text{ (see Fig. 10,)}$$

so that if $3a < b$; $p z < p d$ and the diagram becomes a trapezium, whereby the difference between the stresses on the two edges will decrease if the width of the sleeper increases.

20 The cross-section of such a joint-sleeper with a suspended rail-joint will be nearly equal to that of two joint-sleepers of the usual size.

It is a further novelty and an essential improvement that the central rib of the sleeper holds the ballast beneath the supporting-plates and prevents it from shifting too much. Hitherto in the ordinary superstructures with cross-sleepers such a central rib forming an abutment for the bedding of the ballast has

25 not been made known or employed. If there are any cross-sleepers with middle ribs, then the latter are placed immediately beneath the supporting-plates themselves, where they are rather disadvantageous as far as regards

30 the uniform compression and packing of the ballast beneath the supporting-plates and over the whole widths of the latter, since the material beneath each supporting-plate requires to be packed uniformly, whereas in 35 the hollow cross-sleeper with a central rib having the supporting-plates on both sides according to my invention the ballast beneath each supporting-plate need be packed from one side only.

40 For tracks on which the trains are regularly running in one and the same direction (with the exception of interruptions)—i. e., for all two-track main railroads—the unsymmetric rail-joint is made use of in combination with the special construction of the suspended rail-joint according to my invention. As is well known, in the unsymmetric rail-joint the lengths of the two suspended rail ends are made unequal, and for the purpose aimed 45 at the giving-off rail end is made shorter, so as to reduce as much as possible its deflection under the wheel load, while the taking-up rail end is made longer in order to offer little resistance to its deflection down to that 50 of the other rail end. Then the shocks given to the railroad-cars will be far less violent than when the taking-up rail end is as long as the giving-off rail end. It is true that such a suspended rail-joint in which the free 55 rail ends are unequal is already known, but then the two supporting-plates are invariably placed on separate sleepers, and hence

the free rail ends in such a joint cannot be shortened as abruptly as in the joint on a single sleeper, since sufficient space must be left 70 between the two adjacent sleepers for packing the ballast. The construction of such a joint according to my invention is shown at Fig. 5 in elevation and at Fig. 6 in plan. Let the length of the giving-off rail end be $= 1$ and its 75 deflection $= \delta$ under the load $= P$. Then for the longer taking-up rail end of the length $= l_1$ a smaller load P_1 will be required for producing the same deflection δ , which is found as follows:

$$\delta = \frac{P l^3}{3 E I} = \frac{P_1 l_1^3}{3 E I}$$

Hence

$$P_1 = \frac{l^3}{l_1^3} P. \quad 85$$

For a proportion of 1 to l_1 like two to three the load P_1 and also the reaction of the taking-up rail end against deflection δ will be

$$P_1 = \frac{2^3}{3^3} P = \frac{8}{27} P;$$

and for the proportion being like one to two P_1 would be only

$$\frac{1^3}{2^3} P = \frac{1}{8} P.$$

In this proportion the shocks given to the railroad-cars will be decreased. Were the 100 load P to remain on the longer taking-up rail end of course it would produce a greater deflection than δ —i. e., the wheel would sink—while for rail ends of equal lengths it would perceptibly jump under the influence of the 105 reaction of the elastic resistances. The mechanical work to be performed during the deflection, however, requires a certain time, during which the wheel passes on. The least shock is produced if the longer taking-up rail 110 end of the length l_1 sinks as easily as possible down to the deflection of the giving-off rail end of the length l while still retaining a sufficient power of resistance, so that a deeper sinking 115 of the wheel on the taking-up rail end occurs only at the moment when the wheel has traveled through the distance like the difference of $l_1 - l$ —i. e., occupies a position at the distance of l from the center of the supporting-plate, in which case also the taking-up 120 rail end will deflect equally to the giving-off rail end under the same wheel load. The said difference $l_1 - l$ will have to vary with the varying wheel loads and velocities, and it should be ascertained by calculations and 125 trials under the respective circumstances. The examination of the relations between the mechanical work, the elastic resistances, their durations of time, and the velocities of the railroad-cars does not fall within the scope 130 of this invention, which merely concerns the new technical effect of this perfecting of the unsymmetric suspended rail-joint in reducing the shocks of the railroad-cars.

The novelties and improvements described above in the suspended rail-joint cannot be obtained with the ordinary wooden or iron cross-sleepers. Especially the central rib cannot be arranged in a practical manner when making the sleepers of wood. Preferably the metal joint-sleepers are provided with the usual head-plates on the ends to prevent them from shifting longitudinally.

10 What I claim as my invention, and desire to secure by Letters Patent, is—

1. The combination with two rails arranged end to end and fish-plates connecting their adjacent ends, of a metal sleeper having a central, longitudinal vertical rib on its under surface, and a pair of rail-supporting plates between the sleeper and the rails, said plates being separated from each other and substantially equidistant from the said rib, for 15 the purpose set forth.

2. The combination with two rails arranged end to end and fish-plates connecting their adjacent ends, of a metal sleeper having a central, longitudinal vertical rib on its under 20 surface, and a pair of rail-supporting plates between the sleeper and the rails, said plates being separated from each other and sub- 25

stantially equidistant from the said rib, and the end of one rail extending a greater distance beyond its plate than does the end of the opposing rail beyond its plate, for the purpose set forth. 30

3. In a suspended rail-joint, a metal sleeper having a central longitudinal vertical rib on its under surface, and two rail-supporting 35 plates on the sleeper separated from each other and substantially equidistant from said rib, for the purpose set forth.

4. In a suspended rail-joint, a metal sleeper having a central longitudinal vertical rib on its under surface, and two rail-supporting plates on the sleeper separated from each other and substantially equidistant from said rib, and the width of the sleeper being equal to at least three times the distance from center to center of said plates, for the purpose 40 set forth. 45

In witness whereof I have hereunto signed my name in the presence of two subscribing witnesses.

GOTTFRIED HEINRICH JACOB MAAS.
